UNITED STATES PATENT OFFICE.

WILLIAM HERBERT GRAHAM, OF OAKLAND, CALIFORNIA.

DISAPPEARING OR TELESCOPIC LAWN SPRINKLER.

Application filed December 7, 1925. Serial No. 73,571.

The present invention relates to improvements in sprinklers and has particular reference to disappearing sprinklers such as are commonly used in lawns or golf courses to be normally hidden below the surface of the ground and to project upwardly under the influence of the water pressure whenever the water is turned on. It is proposed as a particular feature of the present invention to 5 provide a self cleaning sprinkler of the character described that automatically cleans the outer face of the pipe adjacent the sprinkler head every time the latter moves from inactive to active position and vice-versa. It is 10 further proposed in the present invention to arrange the sprinkler head relative to a pipe in such a manner that the sprinkler head may be screwed downwardly or upwardly on the pipe for the purpose of increasing or decreasing 15 the flow of water.

Further objects and advantages of my device will appear as the specification proceeds.

The preferred form of my invention is illustrated in the accompanying drawing in 20 which:

Figure 1 shows a side elevation of my sprinkler in inactive position.

Figure 2 is a side elevation of the sprinkler in active position.

Figure 3 is an enlarged section through 25 the sprinkler.

While I have shown only the preferred form of my device, I wish to have it understood that various changes or modifications 30 may be made within the scope of the claims hereto attached without departing from the spirit of the invention.

In the drawing my sprinkler is shown as being connected to a ground system of piping 40 including a horizontal pipe 1 and a vertical pipe 2 rising therefrom. The latter pipe comes within a few inches of the ground surface indicated at 27 and has a reducer 3 threaded thereon as shown at 4. The reduced 45 portion 5 of the reducer slidably receives the pipe 7 of the sprinkler 6 as shown at 9 and supports a collar 10, the horizontal flange 11 of which rests on the flare 9 while the vertical flange 12 confines the packing 13. The 50 fit between the pipe 7 and the reducer 3 is very loose so that a considerable amount of water may be forced through the space between the two elements unless prevented by the packing 13 which, of course, does not become active until the sprinkler has reached 55 its uppermost position.

The top portion of the pipe 7 is threaded as shown at 14 and has a hood 15 screwed thereon with a flange 16 extending downwardly from the hood and serving to check 60 the stream of water passing through the loose fit between the pipe and the reducer and to cause the said water to flow downwardly on the outside of the pipe 7 and of the reducer 3 for keeping the surfaces thereof clean. 65

The sprinkler head is screwed to the top of the pipe 7 and comprises a gland 17 formed with a preferably semi-circular recess in the top face thereof and provided with a threaded flange 19 allowing the cap 21 to be screwed thereon after a diaphragm 20 has been positioned between the cap and the gland. 70

The recess formed in the top of the gland is considerably larger than the circumference of the pipe 7 so that the top face of the gland 75 is presented as a comparatively narrow ring 22 and the diaphragm 20 is formed with a plurality of circumferentially arranged holes 23 disposed just inside of the ring shaped top 22 of the gland but outside of the vertical column of the pipe 7 so that when the gland is screwed downwardly until the bottom face of the diaphragm comes in contact with the top of the pipe 7 the diaphragm forms a closure for the pipe and no water is permitted 80 to pass through the sprinkler. As the gland is screwed upwardly the discharged area for the water increases as the space between the diaphragm and the top of the pipe increases so that the amount of discharged water may 85 be controlled by adjusting the sprinkler head on the pipe 7. In this connection it might be stated that after the desired adjustment has been obtained the hood 15 may be screwed up against the bottom face of the gland and 90 thus serve as a locknut.

The cap 21 is recessed in its bottom face as shown at 24 and has a circular perforation 26 communicating with the recess while spiral passages 25 connects the recess 24 with the perforations 23 of the diaphragm. When 100 connected in the manner shown in Figures 1 and 2 a small casing 28 is preferably provided around the sprinkler head to prevent earth from caving in.

Having described my invention, I claim:

1. In a disappearing sprinkler, a vertical pipe connected to a controlled source of water pressure, an element slidably relative thereto having a sprinkler head at one end thereof and projecting upwardly when the pressure becomes active upon the sprinkler 110

head and an operative connection between the said element and the pipe limiting the upward motion of the former and made to allow water to escape therethrough while the element moves relative to the pipe with a hood on the said element causing the escaped water to flow down the outside of the element and the pipe for cleaning both of them.

2. In a disappearing sprinkler, a vertical pipe connected to a controlled source of pressure, and terminating in a reducer, a second pipe slideable in said reducer having means at its lower end engaging the latter for limiting its upward motion and a sprinkler head at the upper end of the second pipe causing the latter to project upwardly when the pressure becomes active thereon, the second pipe fitting loosely in the reducer so as to allow water to escape between the same while the second pipe is in motion and a hood fixed to the second pipe checking the escaped water and causing the same to flow downwardly on the pipes for cleaning the same.

3. In a sprinkler, a pipe and a sprinkler head threaded thereon, the sprinkler head being formed with outlets outside the periph-

ery of the pipe so as to allow the operative outlet area for the water to be adjusted by threading the head upwardly or downwardly with a lock nut on the pipe below the head formed to present a hood around the pipe checking water squirting from the pipe below and causing the same to return on the outside of the pipe for cleaning the latter.

4. A sprinkler, comprising a hollow body, means for supplying said body with water under pressure, a nozzle slidably mounted in said body, an adjustable sprinkler head on the end of said nozzle, and means locking the sprinkler head in position and for enclosing the joint between the nozzle and the body when the sprinkler is inactive.

5. In a water sprinkler, the combination of a body, a nozzle mounted in said body in telescopic relation therewith, a head adjustably mounted on said nozzle, a plate threaded to said nozzle in engagement with said head and provided with a depending skirt adapted to surround said body when the sprinkler is inactive.

In testimony whereof I affix my signature.
WILLIAM HERBERT GRAHAM.
